BAG CLOSING MACHINE

Robert N. Cundall, deceased, late of Lackawanna, N. Y., by Luta L. Cundall, administratrix, Lackawanna, N. Y., assignor to Consolidated Packaging Machinery Corporation, Buffalo, N. Y., a corporation of New York

Application June 29, 1937, Serial No. 150,907

32 Claims. (Cl. 93—6)

The present invention relates to a machine and method for closing filled paper bags, particularly paper bags adapted to contain from a few ounces up to twenty-five pounds of material. The invention finds particular utility in the formation of packages of coffee, tea, flour, cocoa, chemicals and other products which are either very finely divided so that the products tend to escape from the bag, or aromatic and tend to become stale and rancid if exposed, or hygroscopic, or deliquescent, or otherwise tend to deteriorate if air and moisture are permitted to contact therewith. A feature of the present invention is that packages containing any such product may be readily and perfectly formed regardless of the size of the package or the weight of the product, provision being made in the present machine whereby it may be instantly adjusted to accommodate fluctuations in the density 20 of the product or its degree of compactness within the package. Many such products are affected by atmospheric conditions, or vary in innate characteristics from time to time, so that a unit weight will occupy more or less space within a package. The present invention is designed not only to be adjustable to accommodate different weights of products packaged in different sizes of bags, but also to accommodate fluctuations in density of the compacted product without 25 loss of time in adjustment of the machine.

A feature of the present invention is the compactness of the package forming mechanism, the mechanism whereby the bag mouths are trimmed, creased, folded, provided with adhesive and adhered to the top of the package being condensed practically to a minimum size. In prior machines such mechanism occupied a great number of stations so that a package traveled a long distance through the machine and tended to lose whatever 30 degree of compactness had been imparted to its contents prior to its entry into the machine. In the present invention the filled bag is received from filling mechanism and may be compacted by hand, but is preferably mechanically compacted before it is presented to the machine. The bag is then fed through the machine in three short steps; one step to place the bag mouth in juxtaposition with trimming, creasing and initial folding mechanism, the second step to 35 place the bag mouth in juxtaposition with gluing, folding and pressing mechanism, and the third step to eject the finished package. Preferably, the finished package is ejected into drying mechanism which holds the closure under pressure 40 while the adhesive sets. The compactness of

the machine permits one operator to manage and control the entire combination, and the small number of feeding movements tend to minimize any loosening of the bag contents, especially 5 since provision is made in the machine to retain whatever degree of compactness which has been imparted to the filled bag before its entry into the machine.

A second feature of the present invention is the fact that all operating parts of the closure forming mechanism are fixed in relative position to a vertically adjustable table provided with horizontally adjustable guides so that a wide range of bag sizes may be accommodated merely by adjusting the height of the table and the spacing of 10 the guides, and so that fluctuations in density of the product may be compensated for by a single vertical adjustment requiring one or two seconds 15 to perform.

A further feature of the invention is the provision of bag feeding mechanism operating to feed the bag one step between each operating 20 performance of the closure forming mechanism, requiring about one-fourth, or less, of the rotation of a driving shaft in order that the closure 25 forming operations may be performed in the other three-fourths of the rotation of said shaft and the speed of the machine thereby increased.

A further feature of the invention is the provision of adhesive-applying mechanism which not 30 only applies adhesive to the bags, but aids in the formation of a sharply defined closure whereby leakage is practically eliminated.

An advantage of the present invention resides 35 in the compactness of the machine which, therefore, may be placed in almost any existing packing plant, the machine being from one-third to one-half the size of prior machines for forming a relatively comparable closure. In the present embodiment of the machine illustrated in the 40 drawings, the largest element is the drying table which is substantially circular and which rests upon a standard enclosing a motor and reduction gearing for driving both the closing and drying mechanism. Other types of dryers may 45 be substituted for the rotary type if desirable, the rotary type being preferred because of its compactness.

A further advantage of the present invention and one which is of utmost importance is 50 the ability of the machine to form uniform and efficient closures preventing sifting to a greater degree than any prior known machine.

The present invention is in part an improvement upon the machine disclosed in the copend- 55

ing application of Robert N. Cundall, Serial No. 20,827, filed May 10, 1935. The aforementioned machine, however, includes mechanism for tucking gussets and collapsing the mouth of a bag, whereas in the present machine such mechanism has been eliminated since the capacity of most plants is such as to permit the operator to tuck gussets and collapse the mouth of each bag as it is presented to him by the filling mechanism. The aforesaid machine also comprises an endless chain conveyor, whereas in the present machine the bags are fed by reciprocating paddles. The general purpose of the present machine is the same as in the prior application, but a number of new features are present and a number of old features have been eliminated or simplified.

Referring to the drawings, wherein like numerals refer to like parts throughout, there is disclosed a preferred embodiment of the invention. Other objects and advantages will be apparent from the following disclosure.

In the drawings:

Fig. 1 is a front elevation of the left end of the general combination showing the dryer, the driving means and a portion of the support for the closure forming mechanism, and Fig. 2 is a front elevation of the right end of the machine showing the closure forming mechanism, the two views being separated along line A—A;

Fig. 3 is an end elevation of the machine looking at the right end, certain parts being eliminated in order to clarify other parts;

Fig. 4 is a top plan view of the entire combination;

Fig. 5 is a partial cross-section taken on line 5—5 of Fig. 2;

Fig. 6 is a rear elevation of the closure forming mechanism, the front of which is shown in Fig. 2;

Fig. 7 is a plan view of the one form of gluing and shaping mechanism;

Fig. 8 is a side elevation of the mechanism of Fig. 7;

Fig. 9 is a vertical cross-section taken on line 9—9 of Fig. 2 showing a preferred form of gluing and shaping mechanism together with the final folding and pressing mechanism;

Fig. 10 is a vertical cross-section taken on line 10—10 of Fig. 2 showing the edge trimming, crease forming and initial folding mechanism together with a form of mechanism for removing trimmed edges from the machine;

Fig. 11 is a vertical cross-section taken on line 11—11 of Fig. 9;

Fig. 12 is a vertical cross-section taken on line 12—12 of Fig. 10;

Fig. 12a is a vertical cross-section taken in the plane of the bag mouth;

Fig. 13 is a detailed view of the cam and follower for operating the gluing and shaping mechanism;

Fig. 14 is a detailed view of the cam and follower for operating the final folding and pressing mechanism;

Fig. 15 is a detailed view of the cams and followers for operating the edge trimming, initial folding mechanism and the anvil of the creasing mechanism;

Fig. 16 is a detailed view of the cam and follower for operating the blade of the crease forming mechanism; and

Figs. 17 to 23 inclusive diagrammatically illustrate the formation of a closure by the machine.

Referring to Figs. 1 and 2, the combination comprises closure forming mechanism C extending from one side of the standard of a dryer D,

which standard houses a motor and reduction gearing for driving both parts of the combination. The standard 30 is provided with a removable plate 31 by means of which access to the interior may be had. A motor 32 provided with a variable-speed pulley 33 is fixed to a support 34 pivotally suspended from a bracket 35 on the standard. A hand wheel 36 rotatably attached to standard 30 is screwed onto a screw which passes through a boss 37 at one side of the standard and is pivotally attached to the support 34 whereby to swing motor 32 which causes a belt 38 to engage pulley 33 at varying distances from its center whereby the speed of the belt is adjustably controlled. Belt 38 rotates pulley 39 fixed on the shaft 40 of a reduction gear box 41. A shaft 42 operated at the proper speed drives both the dryer and closure forming mechanism. The pulleys 33 and 39 preferably comprise a well-known type of speed adjusting device.

The dryer

Shaft 42 is provided with a sprocket 45 (Figs. 1, 3 and 4) about which passes a sprocket chain 46 extending about a sprocket 47 fixed to the main drive shaft 48 of the closure forming mechanism. On its return lap chain 46 engages a sprocket 49 fixed to a stub shaft 50 supported in a bearing 51 on standard 30. The end of the shaft extending into the standard carries a bevelled gear 52, while the opposite end is reduced in diameter and forms a support for one end of a rock shaft 53. Gear 55 fixed to a vertical shaft 56 (Figs. 1 and 4) meshes with a bevelled gear 52 which, through an eccentric pin, operates a crank arm 57 located above the standard 30. Crank arm 57 carries a pin 60 upon which is pivotally mounted a pawl 61 and the ends of which are embraced by arms 62 extending from a hub supported by a vertical stud 63. Pawl 61 is provided with an ear 65 to which is pivotally attached a lever 66 provided with a bayonet slot 67 through which extends a fixed pin 68. The free end of lever 66 extends to within reach of the operator and is provided with a handle 69. A spring 70 extending from the lever to a fixed pin tends to keep the pawl 61 in operative position to engage a tooth of a ratchet 71 at each rotation of shaft 56. The pawl may be thrown out of operative position upon outward movement of lever 66 and held at its inoperative position by properly positioning the lever to lock pin 68 in the bayonet slot 67. Continued rotation of shaft 56 will then have no effect upon ratchet 71.

Pawl 61 is of considerable height and ratchet 71 is relatively narrow in order that the height of the dryer, which is rotated by the ratchet, may be vertically adjusted to accommodate all heights of bags within the range of the machine. In order to accomplish the adjustment, the dryer comprises the following: A vertical tube 75 (Fig. 1) is fixed in a socket 76 at the top of standard 30. The tube 75 does not rotate and a bell shaped hood 77 is fixedly supported at the upper end of the tube. A cam 78 is supported by the hub of the hood to remain in fixed position and at a fixed height. A hub 79 is rotatably mounted upon the tube 75 and is fixed at a definite level with respect to cam 78. A disc 80 carried by hub 79 carries a series of dryer plates 81 which are caused to engage the top of each bag presented to the dryer. A rod 85 extends axially of tube 75 and passes through a reducing flange 86 resting on the top of tube 75. The upper end of

rod 86 is threaded and a hand wheel 87, screwed onto the upper end of the rod, rests on coupling 86 and supports the rod in adjusted position relative to the tube. The lower end of rod 85 is slipped through a guiding collar 90 inside of tube 75 which, together with the lower half 91 of a thrust bearing surrounding tube 75, forms a firm guide for the rod. The lower end of rod 85, collar 90 and the lower half 91 of the thrust bearing are fixed together by a bolt 92 passing through vertical slots in tube 75. The upper half 92 of the thrust bearing forms a support for a hub 93 and an integral, depending collar 94 to which is affixed ratchet 71. Collar 93 supports the table 95 upon which the bags are supported. The table comprises a vertical flange 96 and a horizontal ledge 97. A recessed step 98 is provided at the edge of ledge 97 to receive the end of an intermediate hinged extension 100 of the adjustable table of the bag closing mechanism (Fig. 2).

Since the disc 80 is vertically fixed in height, but must rotate with the table 95, a connection is provided comprising a rod 105 fixed in a boss 106 on the lower surface of the disc. The rod extends through a matching opening in the table 95 so that the table and disc rotate together. Rotation of hand wheel 87 lowers the table 95 without disengaging rod 105 from table 95 or pawl 61 from ratchet 71.

In order to form a more completely enclosed machine, table 95 is preferably provided with depending lugs 107 to which is attached a depending skirt 108 fitting over an upwardly extending wall 109 fixed to lugs 110 on standard 30. The entire range of adjustment of the machine is such that the skirt 108 and wall 109 always substantially protect the enclosed mechanism. To carry out the idea of enclosing all working parts, a cup 111 is preferably up-ended over the end of rod 85.

The dryer plates 81 are preferably pivotally mounted on the ends of arms 112 pivotally fixed at 113 to lugs on disc 80. The inner end of each arm is provided with a roller 114 which engages the cam 78 at the proper portion of the cycle to raise the plates whereby to permit the insertion of filled and closed bags. Each arm is provided with an adjustable pin 115 to which is attached a spring 116 by means of which the pressure on the closure may be properly controlled. The opposite end of the spring is attached to a ledge 117 on the edge of disc 80. Each arm 112 is fixed to its plate 81 by means of a pivot pin 118 passing through the arm and a lug 119 on the plate. The arm is for that purpose square and hollow and is preferably provided with limiting extensions at each corner of the hollow square, the extensions being provided to limit the pivotal movement of plate 81. The pivotal movement is provided in order that the plates may adjust themselves to the tops of the bags and thus apply uniform pressure throughout the extent of the closure.

The closure forming mechanism

Shafts 42, 48 and 53 extend from one side of the dryer in substantial parallelism and operate the closure forming mechanism which is supported in a frame consisting of side plates 125 and 126 (Figs. 2, 3 and 6) bolted to the side of support 30, side plate 126 being to the rear of the machine and extending higher than side plate 125, and side plate 125 being formed partially to house and support the gear box 41. The side plates are joined by a lower flange 127 which substantially

completes an enclosure for the shafts and to which is affixed a single supporting leg 128. End bearings for shafts 42, 48 and 53 are provided in the various plates in order to form a rigid structure. Side plate 125 is provided with an opening defined by flanges 129 and 130 to which is attached a pedestal 131 supporting the adhesive applying mechanism. Side plate 126 is also provided with an opening defined by flanges 132 and 133 to which are attached vertical plates 134 and 135, respectively, forming a support for the other working mechanisms. The upper ends of vertical plates 134 and 135 extend over the middle of the machine and are braced by cross rods 136, 137 and 138, which form fixed supports for the operating parts. An intermediate vertical plate 139 is supported by the cross rods and separates the two stations of the machine. A sheet metal hood 140 is fixed to the edges of vertical plates 134 and 135 substantially to enclose the working parts.

The bags are fed through the machine in upright position with their bottoms resting upon a smooth table 145 which is supported by vertical screws 146 mounted in bearings 147 on the side plate 125. An arm 148 extending from a collar loosely positioned on each screw 146 provides a bearing support for a horizontal adjusting shaft 149 which is rotated through bevelled gears by a hand wheel 150. Bevelled gears on shaft 149 and screws 146 translate rotation of hand wheel 150 into vertical movement of table 145. The flanges of table 145 telescope over the upper extremities of side plate 125 in order that a wide range of adjustment may be provided. An extension 155 of table 145 provides the initial support upon which bags may be placed while the mouths are being collapsed and introduced into guides which retain the form of the bag during its entry into the machine.

Bag feeding mechanism

A pair of angles 156 extend from vertical plate 134 with their vertical flanges defining a narrow slot and their horizontal flanges defining shoulder shaping guides at a definite height with respect to the operating mechanisms. The forward extremities of the vertical flanges flare outwardly and the horizontal flanges flare upwardly, and a pair of spaced guide rods 157 extend forward therefrom at the proper height and spacing to receive a filled bag. The operator shapes the mouth of the bag on extension 155 and slides the bag forward onto the end of table 145, the angles 156 squaring and shaping the shoulders of the bag as it is moved into engagement therewith.

The bag is then engaged by the first of three paddles 158 which is swung against the rear surface of the bag and then moved forward the length of one step to bring the bag in line with the first set of operating mechanisms. The means for swinging and moving the paddles comprises the following: Rod 160 (Figs. 3 and 6) supports a bell crank having a short, substantially horizontal arm 161 provided with an elongated slot and a long, substantially vertical arm 162. A pitman 163 adjustably fixed in the slot of arm 161 extends from an eccentric strap surrounding an eccentric 164 fixed to shaft 48. Rotation of eccentric 164 normally rocks the long arm 162 in the direction of movement of the bags through the machine, but the arms 161 and 162 are connected by a slip joint 165 whereby the arm 162 may remain stationary in case of a jam. The end of arm 162 carries a ball which fits a socket at one end of a connecting rod 170, the other end of the rod be-

- ing provided with a socket connected to a ball carried by a bell crank 171 (Fig. 4). The bell crank 171 is pivotally connected to a vertical extension 172 of a slide 173 which is horizontally guided in a dovetail guide 174 fixed to the rear flange of table 145. A link 175 fixed to the free arm of bell crank 171 extends to a crank 176 pinned to a vertical rock shaft 177 (Fig. 3) mounted in a bearing 178 carried by slide 173.
- 10 The upper end of rock shaft 177 extends above the bearing 178 and an arm 179 integral with paddle 158 is pinned thereto. There are three such bearings 178 at evenly spaced intervals, the third bearing extending beyond the end of the slide and being supported by bracing bars 180. Each of the other two bearings supports a vertical shaft and paddle as described, the bearing of each arm 179 being provided with an extension 181 to each of which is pivotally attached a connecting rod 182. Each rotation of shaft 48 pulls connecting rod 170 a certain required distance and then pushes the rod back the same distance, the movements each requiring 180° of revolution of the shaft. However, bell crank 171 and link 175 form a toggle joint which must be straightened before slide 173 moves forward, and bent before the slide moves back. The straightening of the toggle rocks shaft 177 and, through the connecting rod 182, all of the paddles 158 are 20 rocked substantially 90° to engage the rear surfaces of any bags in the machine. The feeding movement of the bags then takes place and the paddles are then returned to initial position. Due to the delayed action provided by the toggle joint the operator has substantially three fourths of a cycle of rotation to place bags and the operating mechanisms are likewise permitted to operate through substantially three fourths of a cycle of rotation, whereby the capacity of the machine is increased by at least one forth of what it would be otherwise. The bag is fed by the first paddle into mechanism for trimming, creasing and initially folding the mouth, by the second paddle into mechanism for applying adhesive, finishing the folding and pressing the bag mouth, and by the third paddle into the drying mechanism. The pivoted extension 100 provides a support for the bag regardless of the adjusted position of table 145 or dryer table 97.
- 50 The angles 156 extend through the first operating station, being reduced in height and width in order to provide clearance. The sides of the bag are restrained by spaced guides 185 adjustably mounted on posts 186 fixed to the table 145 whereby different sizes of bags may be accommodated and maintained in alignment. The upper pair of guides 185 are positioned closely adjacent to the horizontal flanges of angles 156 to assist in the formation of sharply defined shoulders on the bag. As the bag leaves the first station the initial fold is retained by mechanism which will be described and the angles are eliminated as being no longer necessary. After being finally folded and pressed in the second station, 60 the bag is moved by the third paddle under a shoe 186' (Fig. 2) which retains the bag mouth in secured position until the bag is pushed into the drying mechanism.
- At the proper instant with respect to the movement of paddles 158 an empty space on the dryer table is momentarily stopped adjacent the end of table 145. The dryer plate 81 above such space has been elevated by cam 78 and a cam 181 (Figs. 2 and 4) fixed to the vertical plate 135 has leveled the plate. The bag slides under the plate

which is adjustably spaced to engage and maintain the closure, and the dryer table is then rotated one step by ratchet 71. Roller 114 immediately rides off of the cam 78 and the spring 116 causes the determined pressure to be applied to the closure while the adhesive sets. The bag is thus held under compression until removed from the dryer table by curved guides 188, fixed to vertical plate 135, which guide the bags onto a table or conveyor 189 (Fig. 4).

10

The first operating station

The first operating station is illustrated in detail in Figs. 10 and 12, and the mechanism for operating the same is shown in Figs. 6, 15 and 16. Other views may be referred to for correlation of parts.

15

The bag mouth projects upward above the angles 156 which have been reduced in height to less than the distance between the top of the bag contents and the point at which the bag mouth is to be folded upon itself. The distance from the line of folding to the edge of the bag is preferably slightly less than the lower portion. In order to form a tight closure the bag mouth is trimmed and creased at the same time by relatively fixed operating parts. The fixed shear blade 200 is mounted to extend across the space between intermediate vertical plate 139 and vertical plate 134 at the front of a throat or passageway for the mouth of the bag. The movable shear blade 201 is mounted upon a plate 207 and is guided by guiding blocks 203 fixed to the vertical plates. The fixed shear blade is urged into wiping contact with the movable shear blade by a spring fixed in bearing blocks 204 so that constant shearing contact is always maintained. Bearing blocks 205 are also provided to guide the movable shear blade. Shear blade 201 extends above and between blocks 203, and a creasing anvil 206 extends across the same space beneath the blocks. The plate 207 is mounted for sliding movement between guide blocks 203 and is provided with a depending bearing 208 carrying a pivot 209. The plate 207 is recessed at its edges at 210 to receive spaced extensions 211 of a folding member 212 normally maintained in contact with the lower surface of shear blade 201. The extensions 211 are fixed to the upper ends of a yoke member 213 pivotally carried at the ends of the pivot 209. A spring 214 extends from the yoke member to the lower surface of plate 207. Since plate 207 is guided for fixed horizontal movement the spring tends to keep the yoke member at right angles to the plate and thereby holds the folding member 212 against the lower surface of the shear blade. A bolt 215 carried by a fixed extension 225 extends through an opening in yoke member 213 and carries adjustable lock nuts 217 forming an abutment against which the yoke strikes toward the end of the forward movement of the plate. Continued movement of the plate 207 causes the yoke to rock against the tension of spring 214 and thereby causes the folding member 212 to drop downward into its position shown in full line in Fig. 10. The plate 207 is reciprocated through link 216 loosely attached to pivot 209, bell crank 217 pivotally mounted on cross bar 138 and pitman 218. Pitman 218 is fixed to a yoke 219 guided by main shaft 48 and reciprocated in opposite directions by cams 220 and 221 against which bear cam followers 222 and 223, respectively (Figs. 6 and 15).

40

45

50

55

60

65

70

75

The creasing blade 230 which cooperates with creasing anvil 206 to form a crease parallel to the trimmed edge of the bag is carried by a swinging

arm 231 loosely carried by cross rod 136 and reciprocated by a link 232 pivotally connected to a pitman 233 and a toggle link 234 loosely mounted on a cross rod 235 extending from intermediate vertical plate 139 to vertical plate 134. Pitman 233 is connected to a yoke 236 slidably guided by shaft 48 and reciprocated by a cam 237 and cam follower 238 (Figs. 6 and 16).

The edges trimmed from the mouths of the bag 10 are swept toward the rear of the machine by a brush 240 mounted on an arm 241 fixed to a rock shaft 242 which is rocked by crank 243, link 244 and crank 245 (Fig. 10). Crank 245 is fixed to a rock shaft 246 which extends through intermediate vertical plate 139 and carries a crank arm 247 (Fig. 2). The free end of crank arm 247 carries a pawl 248 which is engaged by a tooth 249 carried forward by a reciprocating slide in the second operating station. Due to the arrangement 15 of the linkage described the brush 240 is caused to move toward the rear of the machine and sweeps the trimmings back over the top of blade 201 and plate 207 and onto a sheet metal hood 250 which forms a waste passage together 20 with vertical plates 134, 135 and hood 140. Since the movement of the brush is limited, a spring plate 255 is caused to engage the trimming and assist to move them into the waste passage. The plate 255 is mounted upon an arm 256 pivoted to 25 link 232 and which is urged against an abutment 257 by a spring 258. As link 232 is rocked downward by pitman 233 the arm 256 slides along abutment 257 until the spring plate 255 engages the trimmings on top of the hood 250, the spring plate 30 thereupon moving toward the rear of the machine and urging the trimmings into the waste passage. Other types of trimming ejectors may of course be substituted for the one illustrated and described.

40 During the retraction of the folding member 212 the fold of the bag mouth is retained by a retaining blade mounted upon arm 231. The arm is provided with ears 251 slidably guiding rods 252 which carry the retaining blade 253. Springs 254 placed between ears 251 and the blade 253 tend to 45 keep the blade extended beyond the point of creasing blade 230. As folding member 212 is pulled downward there is sufficient clearance for the fold to be formed, but at the instant that the 50 edge of the bag passes below the retaining blade 253 arm 231 is pulled inward far enough so that the retaining blade will thereafter engage the fold and retain the same as shown in Fig. 10. As the creasing blade continues to move forward springs 55 254 are compressed and the strength of springs 254 is such that movement of the bag is not prevented and the fold will not become disarranged. The folded bag has moved beyond engagement with retaining blade 253 and the next bag has 60 come into position at the instant that the creasing blade engages the creasing anvil 206.

The operation of the first station is as follows: A bag is introduced with its mouth extending up to the shear blades. The movable shear blade 65 then trims the edge and pushes the trimmed mouth slightly forward while the creaser blade and anvil cooperate to form a crease parallel to the trimmed edge. Creaser blade 230 is then retracted while the folding member 212 folds the 70 mouth of the bag as illustrated in Fig. 10. As the shear blade and creasing anvil retract the folding member is raised and moved back to initial position with the blade and anvil. At about the same instant the bag is engaged by the second paddle 75 158 and commences to move forward into the sec-

ond station. During the forward movement of the bag the fold is retained by retaining blade 253 and an auxiliary guide 260 mounted upon the flange of the forward angle 156 (Fig. 5).

Gluing, final folding, and pressing station

The mechanism for applying adhesive, folding the once-folded mouth of the bag down upon the adhesive and pressing the closure into firm adherence is illustrated in Figs. 2, 3, 6, 9 and 11, and 10 details of cams for driving the same are illustrated in Figs. 13 and 14.

Referring to Fig. 9 there is shown a folding and pressing member 265 mounted at the end of spaced arms 266 movable in guides 267 on the vertical plates (Fig. 11). A rod 268 passing through arms 266 at the rear thereof extends into slots 269 in the guides 267. A hardened insert member 271 extending between arms 266 is guided on surfaces 272 of the guides 267 and controls the vertical movement of member 265. A bridge 273 extending between arms 266 provides support for a bail 274 to which is attached a link 275 extending from a bell crank 276 mounted on cross rod 138. A pitman 277 connected to the bell crank is guided by a yoke 278 which is reciprocated by cam 279 on shaft 48 and cam follower 280 (Figs. 6 and 14). Vertical movement of pitman 277 is translated into horizontal movement of member 265, the hardened insert 271 causing the member to fold 30 the bag mouth upon the top of the bag before a rearmost portion of the member comes down to press against the closure. In order to exert uniform pressure upon the folded closure there is provided a rocking socket 285 loosely mounted on cross rod 136, which socket loosely guides the free end of a rod 286 carried by a rocking support 287 pivotally mounted upon a bail 288 carried by a bridge 289 extending across the forward extremities of arms 266. As the arms move forward a 35 spring surrounding rod 286 is compressed and urges the member 265 against the top of the bag as the insert 271 rides off of surfaces 272.

The member 265 is provided with a channel-shaped upper end 290 corresponding to the hooked fingers of a person's hand and slopes downwardly from the end somewhat after the fashion of the palm of a hand and then horizontally to correspond to the heel of a hand. The channel-shaped portion 290 is preferably provided with a 40 flaring mouth to insure guidance of the previously folded bag mouth into the channel. As the member 265 moves forward its action in folding and pressing the mouth of the bag against the shoulders of the bag is almost exactly the action of a 45 person's hand performing the same function.

In order to apply adhesive to the shoulder of the bag upon which the mouth is to be folded and to form a sharply defined closure the following mechanism is employed: Referring to Figs. 2 and 3 there is disclosed an adhesive pot 295 mounted upon standard 131. The pot is preferably mounted above a water tank 296 provided with heating elements in order that thermoplastic adhesives may be used. Mounted to rotate in the adhesive 50 fountain roll 297 driven by a sprocket 298, chain 299 and sprocket 300 on a cross shaft 301. Cross shaft 301 is rotated by a sprocket 302, chain 303 and sprocket 304 on shaft 42. A glue blade 310 mounted on a pivoted bail 311 (Fig. 9) is carried at the ends of spaced levers 312. The glue blade is resilient and extends angularly forward and downward so as to exert a yielding wiping pressure against the shoulder of the bag as it applies adhesive thereto, the adhesive having been 55 60 65 70 75 80 85 90 95

supplied to its under surface by the fountain roll 297. The glue blade is held in proper position by a universally pivoted link 313 extending substantially parallel to levers 312 and connected to the bail 311 and to one end of a bell crank 314 provided with a cam follower 315 held against the surface of a cam 316 mounted on cross shaft 301 by a spring 317. As levers 312 rock backward and forward the link 313 causes the glue blade 310 to follow an arcuate path from its full-line position to its dotted-line position shown in Fig. 3. The cam 316 is so designed as to maintain the glue blade slightly above the surface of the shoulder of the bag as the glue blade moves inward, and then to come sharply down against the shoulder of the bag as the glue blade starts to move outward. At the same instant member 265 commences to fold the mouth of the bag and a regular closure is thus assured.

20 A tucking blade 320 (Fig. 9) carried by resilient fingers mounted on bar 311 extends forward above the glue blade and engages the folded edge of the bag as the glue blade moves inward to insure tucking of the mouth of the bag into the fold. The member 265 is provided with fins 291 which not only depress the tucking blade to insure a tight fold but prevent the blade from snapping upward when released, thereby protecting the resilient fingers. The fins 291 also may guide the mouth 30 of the bag into the channel 290 if the bag is improperly positioned.

Levers 312 are rocked by a pitman 322 connected to a yoke 323 slidably guided by shaft 48 and provided with a cam follower 324 bearing 35 against the operating cam 325 mounted on shaft 48 (Figs. 3, 6 and 13). As the member 265 comes forward to fold the mouth upon the adhesive the glue blade and member 320 are retracted. When the fold is completed member 265 rides forward 40 on top of the fold and presses the closure into firm adherence. During this latter motion the third paddle 158 swings forward to engage the bag, and during the retraction of member 265 the paddle moves the bag beneath shoe 186 (Fig. 2), from 45 beneath which it is pushed into the dryer mechanism by the succeeding bag.

Referring to Figs. 7 and 8 there is disclosed a modified type of glue applying mechanism which has been found to be of advantage. In this modified type the structure is substantially the same except that in place of the fixed member 320 there is provided a resilient tucking blade 330 which is pivotally and adjustably mounted upon blocks 331, loosely carried by the rod 332 joining the ends of levers 312. A cross bar 333 extending beneath and between the blocks 331 is attached to one end of a spring 334 extending to a pin 335 fastened to and extending upward through the bar 311 and through a slot 336 in the tucking blade 330. The pin 335 carries adjustable lock nuts 337 against which the tucking blade 330 is normally urged by spring 334. As the glue blade and tucking blade move forward they are in substantially the positions shown in dotted outline in Fig. 8, thus insuring engagement of the upper fold by the tucking blade. As link 313 is moved downward by cam 316, the rod 332 is rocked thereby easing the upward pressure on tucking blade 330 and facilitating 70 its movement onto the top of the glue blade 310 as member 265 comes forward. The glue blade 310 is preferably provided with a series of small ridges 340 which function to apply cross bars of adhesive tending to trap any material sifting through the mouth of the bag and which also

prevent the glue blade from wiping the adhesive from the top of the bag.

In order to stop the closing mechanism without affecting the dryer, a clutch 350 on shaft 48 (Fig. 6) is provided with a dog 351 engageable by 5 a yielding clutch release pin 352 (Figs. 2 and 3). Pin 352 is fixed to rock shaft 53 which is rocked by a treadle 353 mounted on leg 128, rod 354 and crank 355. As seen in Fig. 3 the forming mechanism is held inoperative. Intermittent operations 10 can be performed by depressing treadle 353. In order to relieve the operator if continuous operation is desired, some means such as hand lever 356 engaging lug 358 on rod 354 may be used which can be locked to keep pin 352 from engaging dog 15 351.

Résumé

Referring to Figs. 17 to 23 inclusive, there is diagrammatically indicated the operation of the machine. In Fig. 17 a bag is shown as positioned by the operator between guides 185 with its mouth collapsed and extending upward between angles 156. Fig. 18 shows the bag at the instant of its arrival at the first station. Fig. 19 shows the bag 25 after its edge has been trimmed and a crease formed parallel to the trimmed edge. Fig. 20 shows the folding member 212 in the act of forming the first fold, and showing the relative position of the glue blade 310 and tucking blade 330 30 which are located at the next station. Fig. 21 shows the bag as it arrives beneath the member 265 with the glue blade and tucking blade moving inwardly. Fig. 22 shows the glue blade and tucking blade at the instant of their being depressed 35 by link 313, and Fig. 23 shows the final pressing position of member 265 and the relative position of the glue blade and tucking blade just prior to the last movement of the bag from the closure forming mechanism. The bag is then positioned 40 beneath a plate on the dryer and after the adhesive has set, is removed from the dryer onto auxiliary table 189 by guides 188.

The present disclosure illustrates and describes the preferred embodiment of the invention. Modifications in arrangement and details of parts will occur to those skilled in the art, and all such modifications are considered to be a part of the present invention as limited and defined by the appended claims.

It is claimed:

1. The method of forming the collapsed upwardly extending mouth of a filled bag into a closure comprising: doubling the mouth of the bag upon itself, restraining the base of the mouth against movement, folding the mouth along its base, applying adhesive to the bag adjacent said base, and applying pressure progressively across the top of the bag in the direction of the fold to press the doubled, folded mouth, the adhesive and 55 the top of the bag together while spreading said adhesive progressively in advance of contact between the doubled folded mouth and the top of the bag.

2. The method of forming a filled bag closure 65 comprising, doubling the mouth of the bag upon itself, placing adhesive on a portion of the bag in the angle between the top of the enclosed contents and the doubled mouth at the side toward which the mouth is doubled, applying pressure to the 70 area of the bag top within said angle, folding the doubled mouth of the bag toward said portion while continuing to press on the top as aforesaid in order to form a sharply defined closure squared with the bag, and applying pressure progressively 75

across the top of the bag and the closure while withdrawing pressure progressively across the bag from within said angle.

3. The method of forming a filled bag closure comprising, forming a crease parallel to the edge upon which the bag mouth may be doubled, doubling the mouth of the bag upon itself, placing adhesive on a portion of the bag in the angle between the top of the enclosed contents and the 10 doubled mouth at the side toward which the mouth is doubled, applying pressure to the top of the bag within said angle, folding the doubled mouth of the bag toward said portion while continuing to press on the top as aforesaid in order to 15 form a sharply defined closure squared with the bag, and applying pressure progressively across the top of the bag and the closure while withdrawing pressure progressively across the bag from within said angle.

20 4. The method of forming a filled bag closure comprising, trimming the edge of the bag mouth and forming a crease parallel to the trimmed edge upon which the bag mouth may be doubled, doubling the mouth of the bag upon itself, placing 25 adhesive on a portion of the bag in the angle between the top of the enclosed contents and the doubled mouth at the side toward which the mouth is doubled, applying pressure to the top of the bag within said angle, folding the doubled 30 mouth of the bag toward said portion while continuing to press on the top as aforesaid in order to form a sharply defined closure squared with the bag, and applying pressure progressively across the top of the bag and the closure while withdrawing pressure 35 progressively across the bag from within said angle.

5. The method of forming a filled bag closure comprising, collapsing the mouth of the bag upon itself to bring the bag mouth into a single plane 40 extending upward above the contents of the bag, trimming the edge of the bag mouth and forming a crease parallel to the trimmed edge upon which the bag mouth may be doubled, doubling the mouth of the bag upon itself, placing adhesive on 45 a portion of the bag in the angle between the top of the enclosed contents and the doubled mouth at the side toward which the mouth is doubled, applying pressure to the top of the bag within said angle, folding the doubled mouth of the bag to- 50 ward said portion while continuing to press on the top as aforesaid in order to form a sharply defined closure squared with the bag, and applying pressure progressively across the top of the bag and the closure while withdrawing pressure pro- 55 gressively across the bag from within said angle.

6. The method of forming a filled bag closure comprising, collapsing the mouth of the bag upon itself to bring the bag mouth into a single plane 60 extending upward above the contents of the bag, trimming the edge of the bag mouth and forming a crease parallel to the trimmed edge upon which the bag mouth may be doubled, doubling the mouth of the bag upon itself, placing adhesive on a portion of the bag in the angle between the 65 top of the enclosed contents and the doubled mouth at the side toward which the mouth is doubled, applying pressure to the top of the bag within said angle, folding the doubled mouth of the bag toward said portion while continuing to 70 press on the top as aforesaid in order to form a sharply defined closure squared with the bag, applying pressure progressively across the top of the bag and the closure while withdrawing pressure 75 progressively across the bag from within said

angle, and confining the closure while the adhesive sets.

7. An operating station of a filled bag closing machine comprising a controlling blade movable to and from a position adjacent the collapsed mouth of the bag and a folding member movable transversely of said collapsed mouth to initiate a fold in the same along said controlling blade and being yieldingly biased toward the bag body so as to yieldingly press and smooth said collapsed and folded mouth upon the top of the bag.

8. In a final folding station of a filled bag closing machine, a folding member comprising means to initiate a final fold and a pressing 15 plate, means operable to move said folding member to initiate a fold and to position said pressing plate over the folded end of the bag, means to yieldingly press said plate upon the top of the bag, the operation of said moving means and said 20 yielding means overlapping whereby said plate smooths and presses the folded end of the bag upon the top thereof.

9. A machine for closing the mouths of filled bags having the side walls of their open ends 25 tucked inwardly and the front and rear walls collapsed upon the tucked side walls comprising a creasing device adapted to form a crease in the collapsed end of a bag a certain distance above the enclosed contents, means movable transverse- 30 ly of the creased end of the bag to fold the end of the bag once upon itself along said crease, means to apply adhesive to a portion of the bag and means including a member movable to exert yielding and sliding pressure upon the folded end 35 of the bag to press the same upon the adhesive-bearing portion and to draw the bag taut.

10. In a filled bag closing machine, a member adapted to operate upon a bag having its open mouth collapsed and doubled upon itself, said 40 member comprising a channel adapted to guide and retain said doubled mouth in doubled condition, and pressing means adjacent said channel; means yieldingly urging said pressing means toward the top of a bag and means restraining said 45 yielding means; means to move a bag to said member; means to guide the doubled mouth of the bag into said channel; and means to move said member across the bag to cause a wall of said channel to fold said doubled mouth toward 50 the top of the bag, to release said yielding means from said restraining means, and to slide said yieldingly urged pressing means across the top and folded mouth of the bag.

11. An operating station of a filled bag closing 55 machine comprising means to retain the bag in upright position with the mouth of the bag extending upward therefrom, a first blade mounted at one side of the bag mouth, a slide carrying a second blade at the other side of the bag mouth, 60 means to reciprocate said slide whereby to cause said blades to trim the edge of the bag mouth, a creasing member mounted beneath said second blade, a second creasing member movably mounted beneath said first blade, means to re- 65 ciprocate said second creasing member whereby to cause said creasing members to form a crease in the bag mouth parallel to the trimmed edge substantially at the instant of shearing, and means to double the bag mouth along said crease. 70

12. An operating station of a filled bag closing machine comprising means to retain the bag in upright position with the mouth of the bag extending upward therefrom, a first blade mounted at one side of the bag mouth, a slide carrying a 75

- second blade at the other side of the bag mouth, means to reciprocate said slide whereby to cause said blades to trim the edge of the bag mouth, a creasing member mounted beneath said second blade, a second creasing member movably mounted beneath said first blade, means to reciprocate said second creasing member whereby to cause said creasing members to form a crease in the bag mouth parallel to the trimmed edge substantially at the instant of shearing, means to double the bag mouth along said crease, and means to retain the bag mouth in doubled form while the bag moves to the next station of the machine.
13. An operating station of a filled bag closing machine comprising means to retain the bag in upright position with the mouth of the bag extending upward therefrom, a first blade mounted at one side of the bag mouth, a slide carrying a second blade at the other side of the bag mouth, means to reciprocate said slide whereby to cause said blades to trim the edge of the bag mouth, a creasing member mounted beneath said second blade, a second creasing member movably mounted beneath said first blade, means to reciprocate said second creasing member whereby to cause said creasing members to form a crease in the bag mouth parallel to the trimmed edge substantially at the instant of shearing, and means carried by said slide to double the bag mouth along said crease.
14. An operating station of a filled bag closing machine comprising means to retain the bag in upright position with the mouth of the bag extending upward therefrom, a first blade mounted at one side of the bag mouth, a slide carrying a second blade at the other side of the bag mouth, means to reciprocate said slide whereby to cause said blades to trim the edge of the bag mouth, a creasing member mounted beneath said second blade, a second creasing member movably mounted beneath said first blade, means to reciprocate said second creasing member whereby to cause said creasing members to form a crease in the bag mouth parallel to the trimmed edge substantially at the instant of shearing, means carried by said slide to double the bag mouth along said crease, and means to retain the bag mouth in doubled form while the bag moves to the next station of the machine.
15. An operating station of a filled bag closing machine comprising a slide, means to reciprocate said slide into operative position with respect to the mouth of a filled bag, a blade mounted on said slide for trimming the edge of the bag mouth, a creasing member mounted adjacent said slide for forming a crease parallel to the trimmed edge, a folding member mounted on said slide, and means to cause said folding member to double the mouth of the bag along said crease immediately after operation of said blade and creasing member.
16. An operating station of a filled bag closing machine comprising a slide mounted at one side of said station, means to reciprocate said slide across said station into operative position with respect to the mouth of a filled bag, a blade mounted on said slide and a cooperating blade at the opposite side of said station for trimming the edge of the bag mouth, a creasing member mounted adjacent said slide and a cooperating creasing member at the opposite side of said station for forming a crease parallel to the trimmed edge, a folding member mounted on said slide and normally extending into the space
- between the blade and the creasing member carried thereby, means to retain said folding member in normal position, and means to cause said folding member to move downwardly immediately after operation of said blades and creasing members whereby to double the trimmed mouth of the bag along said crease.
17. An operating station of a bag closing machine for operating upon a filled bag, the mouth of which has been doubled upon itself, comprising an adhesive-applying blade, means to cause said blade to apply adhesive to a portion of the bag in the angle between the top of the enclosed contents and the double mouth at the side toward which the mouth is doubled, means to press said blade upon the enclosed contents within said angle, a folding member, means to reciprocate said member across the top of the bag to fold the doubled mouth toward the adhesive-bearing portion, and means associated with said folding member to apply pressure to the top of the bag across the bag while progressively withdrawing said adhesive-applying blade progressively across the bag.
18. An operating station of a bag closing machine for operating upon a filled bag, having an upstanding mouth which has been doubled upon itself, comprising a blade at the side of said station toward which the mouth has been doubled, means to cause said blade to press the apex of the angle between the top of the enclosed contents and the upstanding mouth whereby to define a fold line, a folding member and means to move said member across the top of the bag to bend the upstanding mouth along said defined fold line and toward said blade, said member being yieldably biased toward said bag whereby to exert yielding pressure against said bag top.
19. An operating station of a bag closing machine for operating upon a filled bag, the mouth of which has been doubled upon itself, comprising a blade at the side of said station toward which the mouth has been folded, means to cause said blade to approach the apex of the angle between the top of the enclosed contents and the doubled mouth whereby to form a sharply defined angle, a folding member at the opposite side of said station, means to reciprocate same member across the top of the bag to fold the doubled mouth toward said blade, and means associated with said folding member to apply pressure to the top of the bag progressively across the bag toward said blade while withdrawing said blade progressively across the bag.
20. An operating station of a bag closing machine for operating upon a filled bag, the mouth of which has been doubled upon itself, comprising a blade at the side of said station toward which the mouth has been folded, means to cause said blade to approach the apex of the angle between the top of the enclosed contents and the doubled mouth, means to draw said blade down upon the top of the enclosed contents within said angle to apply pressure thereto and to form a sharply defined angle, a folding member at the opposite side of said station, means to reciprocate said member across the top of the bag to fold the doubled mouth toward said blade, and means associated with said folding member to apply pressure to the top of the bag progressively across the bag toward said blade while withdrawing said blade progressively across the bag.
21. An operating station of a bag closing ma-

chine for operating upon a filled bag, the mouth of which has been doubled upon itself, comprising a source of adhesive, a blade at the side of said station toward which the mouth has been folded, means to cause said blade to transfer adhesive from said source to a portion of the bag in the angle between the top of the enclosed contents and the doubled mouth, means to press said blade upon the part of the bag above the

5 10 enclosed contents within said angle, a folding member at the opposite side of said station, means to reciprocate said member across the top of the bag to fold the doubled mouth toward said blade, and means associated with said folding member to apply pressure to the top of the bag 15 progressively across the bag toward said blade while withdrawing said blade progressively across the bag.

22. A filled bag closing machine comprising two 20 operating stations, and means to feed a filled bag through said stations, the first of said stations comprising means to double the bag mouth upon itself, and the second of said stations comprising means to apply adhesive to a portion of 25 the bag in the angle between the top of the enclosed contents and the doubled mouth at the side toward which the mouth is doubled, means to apply pressure to the portion of the bag within said angle above the contents, means 30 to fold the doubled mouth toward the adhesive-applying means and means to apply pressure progressively across the top of the bag in the direction toward which the mouth is folded while withdrawing the pressure-applying means from 35 within said angle in substantially one continuous operation.

23. A filled bag closing machine comprising two operating stations, and means to feed a filled bag through said stations, the first of said 40 stations comprising means to trim the edge of the bag mouth, means to clear trimmings from the machine, means to form a crease in the bag mouth parallel to the trimmed edge and means to double the bag mouth along said crease substantially in one continuous operation, and the second of said stations comprising means to apply adhesive to a portion of the bag in the angle between the top of the enclosed contents and the doubled mouth at the side toward which the 45 mouth is doubled, means to apply pressure to the portion of the bag within said angle above the contents, means to fold the doubled mouth toward the adhesive-applying means and means to apply pressure progressively across the top of the bag in the direction toward which the mouth is folded while withdrawing the pressure-applying means from within said angle in substantially one continuous operation.

24. The method of closing a filled bag comprising collapsing the unfilled upwardly extending mouth portion thereof into a plane substantially normal to the plane of the top of the enclosed contents, restraining said collapsed mouth against movement along the line defined by the intersection of said mouth and the plane of the contents, applying adhesive to the bag, folding said mouth along said line of intersection and applying pressure to press the mouth, the adhesive and the top of the bag together while 50 releasing the restraint of the mouth.

25. The method of closing a filled bag having the side walls of its open mouth tucked inwardly and the front and rear walls collapsed thereupon into a plane substantially normal to the plane of the enclosed contents, comprising restraining

said collapsed mouth along a line forming the apex of the angle between said collapsed mouth and the top of the contents of the bag, applying adhesive to the bag in the plane of the contents and adjacent said mouth, folding said mouth along said line and applying pressure to press the mouth, the adhesive and the top of the bag together while releasing the restraint along said line.

26. The method of closing a filled bag comprising collapsing the unfilled, upwardly extending mouth portion thereof into a plane substantially normal to the plane of the top of the enclosed contents; applying pressure along the line defined by the intersection of said mouth and the plane of the contents to define a fold line, applying adhesive to the portion of the bag overlying the plane of the top of the enclosed contents, folding said mouth along said defined fold line into contact with the adhesive and the portion of the bag overlying the plane of the enclosed contents.

27. The method of closing a filled bag comprising collapsing the unfilled, upwardly extending mouth portion thereof into a plane substantially normal to the plane of the top of the enclosed contents; restraining said collapsed mouth against movement along the line defined by the intersection of said mouth and the plane of the contents and simultaneously exerting a downward pressure over the bag top between the line of restraint and one wall of the bag; bringing said collapsed mouth toward the plane of the contents by folding the material of the bag substantially along the line of such restraint; removing said restraint while progressively relieving said pressure across the top of said bag from said line of restraint towards said wall of the bag; and pressing said folded mouth into contact with the top of said bag.

28. A machine for closing a filled bag having the side walls of its open mouth tucked inwardly and the front and rear walls collapsed thereupon into a plane substantially normal to the plane of the enclosed contents, comprising a blade, means to move said blade into contact with said bag along a line forming the apex of the angle between said collapsed mouth and the top of the contents of the bag, said blade serving to restrain said collapsed mouth against movement in one direction, a folding member and means to move the same towards said blade into contact with said collapsed mouth to fold said mouth along said line, means to withdraw said blade from said bag after the initial folding of said mouth, and means to cause said folding member to yieldingly press said folded mouth against the top of said bag.

29. A machine for closing a filled bag having the side walls of its open mouth tucked inwardly and the front and rear walls collapsed thereupon into a plane substantially normal to the plane of the enclosed contents, comprising an adhesive-applying blade, means to move an edge of said blade into contact with said bag along a line forming the apex of the angle between said collapsed mouth and the top of the contents of the bag, said blade serving to restrain said collapsed mouth against movement in one direction, a folding member and means to move the same across 60 said bag into contact with said collapsed mouth whereby to fold said mouth along said line, means to move said blade across the top of said bag and away from said collapsed mouth whereby to deposit adhesive upon the top of the bag, and 65

means to cause said folding member to press said folded mouth, said adhesive and the top of the bag together.

30. The method of closing a filled bag comprising collapsing the unfilled upwardly extending mouth portion thereof into a plane substantially normal to the plane of the top of the enclosed contents, folding said collapsed upwardly extending mouth portion upon itself along a line parallel to said plane of the top of the contents to bring a free edge of said folded portion adjacent to said plane of the top of the contents, then applying pressure to said bag along a line defined by the intersection of the upstanding portion of said mouth and the plane of the contents to define a fold line, restraining said free end of said folded portion of the mouth against unfolding, folding the entire upstanding portion of said mouth along said defined fold line and pressing the mouth against the top of the bag while releasing said free end from restraint.

31. The method of closing a filled bag comprising collapsing the unfilled upwardly extending mouth portion thereof into a plane substan-

tially normal to the plane of the top of the enclosed contents, applying pressure along the intersection of said mouth and the bag material overlying the plane of the contents to define a fold line, applying adhesive to a portion of the bag on one side of said fold line, folding said mouth along said fold line so as to bring into contact the portion of the bag carrying said adhesive and a portion of the bag on the other side of said fold line.

32. The method of closing a filled bag comprising collapsing the unfilled upwardly extending mouth portion thereof into a plane substantially normal to the plane of the top of the enclosed contents, applying pressure directly along the intersection of said mouth and the bag material overlying the plane of the contents to define a fold line, then applying pressure to the collapsed mouth portion to fold said collapsed mouth portion along said line and into said plane of the contents.
